UNITED STATES PATENT OFFICE

EDWARD J. BROOKS, OF EAST ORANGE, NEW JERSEY.

BOTTLE-SEAL.

No. 806,519.

Specification of Letters Patent.

Patented Dec. 5, 1905.

Application filed August 30, 1905. Serial No. 276,381.

To all whom it may concern:

Be it known that I, EDWARD J. BROOKS, a citizen of the United States of America, and a resident of East Orange, in the State of New Jersey, have invented a new and useful Improvement in Bottle-Seals, of which the following is a specification.

This invention relates to means for securing the closures of bottles, jugs, demijohns, carboys, and the like, all of which are herein termed "bottles," against violation by insuring the detection of any tampering therewith.

The present invention is more particularly additional to the improvement in bottle-seals described and claimed in my specification forming part of United States Letters Patent, No. 794,849, dated July 18, 1905, and to that species represented by Figures 3 and 4 of the drawings referred to in said specification.

20 The present invention consists in certain novel combinations of parts hereinafter described and claimed. Its objects are to adapt a skeleton bottle-seal for use in connection with caps of any approved kind more securely 25 depressed within the mouth of the bottle, to adapt the seal to interlock in an effective manner with a shoulder at the lower extremity of the head of the bottle, and to adapt the improved seal to be made in quantities at a low 30 cost.

A sheet of drawings accompanies this specification as part thereof.

Figs. 1 and 2 are respectively top and bottom views of the improved bottle-seal as it 35 leaves the factory. Fig. 3 is a side view of the same, and Fig. 4 is a sectional view of a bottle provided with the improved seal.

Like reference characters refer to like parts in all the figures.

40 The improved bottle-seal shown detached by Figs. 1, 2, and 3 and at A in Fig. 4 is combined in use with a bottle B of any kind having a depressed cap-supporting surface 1 within its mouth some distance below its lip 2, a circumferential shoulder 3 at the lower extremities of its head, and a relatively contracted neck 4. It is also combined in use with a cap C, Fig. 4, adapted to rest upon said depressed surface 1 and to serve as the closure of the bottle or to 45 supplement a cork D or other approved main stopper beneath the same. Such cap C may be of paper, cork, wood, metal, or other approved material.

The improved seal, to which the novelty of 55 the invention is confined, comprises a flexible shackle a, of wire or the like, a compressible

seal part b, of suitable soft metal, known as "lead," fast on one end of said shackle and perforated for the passage of the other shackle end therethrough, and a pair of stamped strips c and d, of tin-plate ("tin") or other sufficiently-stiff sheet metal, which are the principal parts and are of one and the same pattern. Said strips c and d cross each other at mid-length and are there fixedly united with each other by a plurality of eyelet-punchings 5, extending through both strips. Before they are so united each strip is provided with a pair of deep indentations forming projections 6 to contact with the cap C on both sides of the intersection of the strips, also with permanent bends 7 and 8, fitted, respectively, to the lip 2 and shoulder 3 of the size and style of bottle for which a given pattern of seal is intended, and, finally, with extremities 9, having outwardly-projecting staples 10 integral therewith, through which the shackle a extends.

The parts of the seal are conveniently united with each other, as in Figs. 1, 2, and 3, at the factory, and the seal A as a whole is quickly applied to the filled bottle B, as in Fig. 4, at the bottling establishment. With the depressed cap C in place the seal A is slipped over the head of the bottle, the free end of the shackle a is threaded through the seal part b, and the shackle is drawn taut, and a seal-press is then applied to the seal part b, so as to permanently fasten the same and to provide the seal part with a distinguishing press-mark, (represented by H in Fig. 4.) In the fastened device, Fig. 4, the projections 6 of the seal-strips c and d contact with the top of the depressed cap C, their bends 8 embrace the shoulders 3 of the bottle-like hooks, and disengagement of said bends is prevented by the interaction of the seal part b, shackle a, and strip extremities 9. In opening the bottle the shackle a is cut or broken, and the seal part b examined to determine the integrity of the contents.

The shackle a and seal part b may obviously be of any known or improved make, and other like modifications will suggest themselves to those skilled in the art.

Having thus described said improvement, I claim as my invention and desire to patent under this specification—

1. A bottle-seal having, in combination with a flexible neck-embracing shackle, and a seal part for inseparably uniting the ends of said shackle, a pair of cap-forming strips crossed at mid-length and each provided with deep in-

dentations on both sides of their intersection forming projections to contact with a disk within the mouth of the bottle and permanent bends adapting them to interlock with a shoulder at the lower extremity of the head of the bottle, and further provided at their lower ends with means whereby they are interlocked with said shackle.

2. A bottle-seal having, in combination with a flexible neck-embracing shackle, and a seal part for inseparably uniting the ends of said shackle, a pair of cap-forming strips crossed and united with each other at mid-length and each provided with deep indentations on both sides of their intersection forming projections to contact with a disk within the mouth of the bottle and permanent bends adapting them to interlock with a shoulder at the lower extremity of the head of the bottle, and further provided at their lower ends with means whereby they are interlocked with said shackle.

3. A bottle-seal having, in combination with a flexible neck-embracing shackle, and a seal part for inseparably uniting the ends of said shackle, a pair of cap-forming strips crossed and fixedly united with each other at mid-length and each provided with deep indentations on both sides of their intersection forming projections to contact with a disk within the mouth of the bottle and permanent bends adapting them to interlock with a shoulder at the lower extremity of the head of the bottle, and further provided at their lower ends with outwardly-projecting staples integral with the strips through which said shackle extends around the neck of the bottle below said shoulder, substantially as hereinbefore specified. 25 30 35

EDWARD J. BROOKS.
